US0D1113275S

(12) **United States Design Patent** (10) **Patent No.:** **US D1,113,275 S**
(45) **Date of Patent:** **** Feb. 17, 2026**

(54) **DRAWER UNIT**

(71) Applicant: **ShenZhen YiHong Technology Co., LTD**, Guangdong (CN)

(72) Inventor: **Yi Dai**, ShenZhen (CN)

(73) Assignee: **ShenZhen YiHong Technology CO., LTD**, ShenZhen (CN)

(**) Term: **15 Years**

(21) Appl. No.: **29/895,751**

(22) Filed: **Jun. 26, 2023**

Related U.S. Application Data

(62) Division of application No. 29/883,730, filed on Feb. 2, 2023, now Pat. No. Des. 990,952.

(51) **LOC (15) Cl.** **06-06**

(52) **U.S. Cl.**

USPC **D6/705**; D3/297

(58) **Field of Classification Search**

USPC D6/668, 627, 675, 672, 705; D3/295-298, 273

See application file for complete search history.

(57) **CLAIM**

The ornamental design for a drawer unit as shown and described.

DESCRIPTION

FIG. 1 is a perspective view of a drawer unit showing my new design;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective top view of the drawer unit showing an inner container sliding out of a housing.

The broken lines illustrate portions of the drawer unit that form no part of the claimed design.

1 Claim, 7 Drawing Sheets
